PERPETUAL DATE CALENDAR

Josua Gabriel Paulin, Nockeby, Sweden

Application April 1, 1936, Serial No. 72,160
In Sweden April 9, 1935

18 Claims. (Cl. 40—112)

My invention relates to perpetual date calendars for automatically indicating the correct date. A calendar of this type usually comprises a week-day member, a date member, a month member and a year member, which may have the form of coaxial, revoluble discs or rings, although cylinders, endless bands or other suitable components may be used. These members are provided with week-day, date, month and year indications, usually arranged in continuous circuits, or they may be connected to or coupled with members provided with such indications. The change-over takes place once in every twenty-four hours, either by hand or from a time-keeper, in the latter case usually at twelve o'clock in the night. The week-day member is then always shifted one week-day step and the date member always at least one date step. The month member may be adapted to be shifted responsive to the movement of the date member in such manner, that for each time the date member is shifted from the thirty-first to the first the month member is shifted one month step. The year member may likewise be adapted to be shifted responsive to the movement of the month member so that each time the month member is shifted from December to January the year member is shifted one year step. The movements of the week-day, month and year members are uniform, i. e., these members are always shifted only one step at a time. The movement of the date member on the other hand is not uniform and therefore is more difficult to accomplish. At the change-over from a month having thirty-one days to the next month the shifting of the date member can be accomplished in the normal way by means of a single step feed. At the change-over from a month having thirty days to the next month, however, there is required, in addition to the normal single step feed, a surplus feed of one step, thus from the 30th direct to the first. Similarly at the change-over from February to March a surplus feed of three steps is required, i. e., direct from the 28th to 1st. If the calendar is also to allow for leap year, then it must be arranged, once in every period of four years, to shift the date member from the 29th direct to the 1st, i. e., one normal step and two surplus steps.

The surplus feed of the date member may be effected by the same feed mechanism which effects the normal feed of the date calendar or by a separate feed mechanism and is usually controlled by the month member through the intermediary of more or less complicated devices.

My invention has for its object to provide a mechanism for effecting the surplus feed of the date member which is simple in construction and reliable in function. For this purpose I provide the month member with a surplus feed control curvature having deflections at points so disposed, when in operative positions, relatively to the date member as to correspond with those positions of the date member in which a surplus feed is required and operative to cooperate with the feed mechanism for the date member for controlling the surplus feed. If the date member has thirty-one continuous date steps no curvature deflections are needed for the January, March, May, July, August, October and December months, which require no surplus feed. For each of the April, June, September and November months, which require a surplus feed of one date step, I provide a curvature deflection so disposed when in the operative position, as to initiate a surplus feed action on the 30th. For a February month having twenty-eight days and requiring a surplus feed of three date steps I provide a deflection so disposed, when in the operative position, as to initiate a surplus feed action on the 28th. This deflection has to be displaced relatively to the aforesaid deflections, not only an extent or an angle corresponding to the difference in month steps but also an extent or an angle corresponding to two date steps. For a February month having twenty-nine days and requiring a surplus feed of two date steps I provide a deflection so disposed, when in the operative position, as to initiate a surplus feed action on the 29th. This deflection has to be displaced relatively to the deflections causing a surplus feed of one date step not only an extent or an angle corresponding to the difference in month steps but also an extent or an angle corresponding to one date step.

The deflections may be obtained by the use of cams or indentations, and the peripheral lengths of these cams or indentations may be utilized for maintaining the feed mechanism in engagement with the date member during the surplus feed so that the surplus feed is effected responsive to the length of the cams or indentations. Thus if the date member has thirty-one continuous date steps and if the feed mechanism has an active feed movement corresponding to about four date steps, then the cams or indentations for a surplus feed of one, two or three steps are given a peripheral length corresponding to about one, two or three date steps.

When controlling the surplus feed in this man-

ner responsive to the length of the cams or indentations of the month member there is, however, the following difficulty to take into account. The shifting of the date member from the 28th of February to the 1st of March represents four date steps, i. e., one normal step and three surplus steps. These three surplus steps represent an angle displacement of the date member $=\frac{1}{31}$ of the whole periphery $=\frac{1}{31} \times 360$ about 10 35° . As the surplus feed is to be effected responsive to the length of the cams or indentations, the February cam or indentation should have a peripheral length corresponding to an angle of about 35° . If however the month member for 15 each shifting is to be turned $\frac{1}{2}$ of a complete revolution $=30^\circ$, then the February cam or indentation cannot be given the required length corresponding to an angle of 35° , as in that case it would encroach upon the part of the month curvature reserved for the following month. This 20 difficulty may be overcome in different ways, for example by making the February cam or indentation somewhat shorter than the length which corresponds to a full surplus feed and to effect the rest of the surplus feed by means of the ordinary feed movement. The feed member of the feed mechanism which effects the normal one step feed of the date member is then adapted to come into operation somewhat earlier than otherwise necessary for effecting the normal feed of 25 the date member. The said difficulty may also be overcome by the use of snap mechanisms which complete the movement of the date member. It is also possible to provide the date member with two consecutive series of date steps, so that the angle displacement of the date member relatively the month member is halved.

The feed mechanism for the date member may comprise two feed members, one for effecting the normal one step feed and one for effecting the surplus feed of the date member. The surplus feed member may be adapted to cooperate directly with the curvature of the month member by moving along this curvature. On the other hand it is possible to use only one feed member which effects not only the normal but also the surplus feed of the date member and in that case I prefer to provide a separate surplus feed control member which is adapted to move along the curvature of the month member and cooperate with the surplus feed member for controlling the surplus feed.

In the accompanying drawings are illustrated two of various possible embodiments of my invention. Fig. 1 shows a front view of the one embodiment with part of the front frame plate broken away to show the interior of the mechanism, Fig. 2 shows a section along line II-II in Fig. 1 with the driving member raised to the position indicated at A and Fig. 3 shows a section along line III-III in Fig. 1. Fig. 4 shows a front view of the second embodiment with part of the front frame plate broken away, Fig. 5 shows a section along the line V-V in Fig. 4 with the driving member raised to the vertical position and Fig. 6 shows a section along line VI-VI in Fig. 4. Fig. 7 shows a section along line VII-VII in Fig. 5 and with the driving member in the position indicated at A in Fig. 4. Fig. 8 is a detail view of the driving member shown in Figs. 4-7 removed; and, Fig. 9 is a fragmentary front view of the calendar.

In Figs. 1-3 the numeral 1 denotes the rear frame plate of the calendar work and 2 the front frame plate, part of which has been broken

away to show the interior of the mechanism. The plates are held together by four posts 3 secured to the plates by means of screws 4. In holes 5 and 6 in the frame plates is revolubly mounted a shaft 7 on which the main parts of the calendar mechanism are mounted.

8 denotes the week-day member which is revolubly mounted on the shaft 7 adjacent the rear frame plate and provided with seven equidistant notches 9. Adjacent the week-day member is mounted the date member 10 which is also revolubly on the shaft 7 and provided with thirty-one teeth 11. The date member is also provided with two pins 12 and 13, the functions of which will be explained in the following.

On the shaft 7 is further revolubly mounted a hub 14 to which is riveted a gear wheel 15 having twelve teeth 16, further the month member 17, which at its periphery is provided with the surplus feed control curvature having four indentations 18 of equal length and an indentation 19 which has about three times the length of the indentations 18. The indentations 18 correspond to the thirty day months April, June, September and November, and the indentation 19 corresponds to the February month. Pivotaly supported at the month member 17 by means of a screw 20 is an arm 21, the free end of which is formed into a leap year control member 22 adapted to cooperate with the indentation 19. The leap year control member 22 is provided with a projection 23 adapted to bear against a leap year member to be described in the following. Movement of the arm 21 in the outward direction is limited by a stop pin 24 secured to the month member. Between the gear wheel 15 and the month member 17 the hub 14 is provided with teeth 25.

The shaft 7 further carries rigidly secured thereto and in the same plane as the leap year control member 22 a leap year member 26 provided with three equidistant cams 27. To the leap year member is riveted a gear wheel 28, which in Fig. 1 is shown as partly broken away.

Adjacent the front frame plate 2 is further revolubly mounted on the shaft 7 a driving member 29. To the driving member are fixed three posts 30, 31, 32, each carrying a pawl 33, 34, 35 revolubly secured to the posts by means of screws 36, 37, 38. Each pawl is provided with a pin 39, 40, 41 engaged by a leaf spring 42, 43, 44 attached to the posts by means of rivets 45, 46, 47. The post 30 is long enough to enable the pawl 33 to cooperate with the week-day member 8 and similarly the post 31 is long enough to enable the pawl 34, the normal feed member, to cooperate with the date member 10. The pawl 35, the surplus feed member, is adapted to cooperate with the month member 17 and the leap year control member 22 and is provided with an extension 48 long enough to cooperate with the pin 12 on the date member 10.

To the rear frame plate 1 is by means of screws 49 fixed a guide member 50 which is adapted to cooperate with the pawl 34. The effective part of the guide member 50 is therefore raised from the rear frame plate to the plane of the pawl 34, at the same time providing a clearance space for the week-day member 8.

The driving member 29 together with the pawls 33, 34, 35 forms the feed mechanism.

To the rear frame plate 1 is further by means of screws 51 fixed an angle support 52 carrying a gear wheel 53 revolubly secured to the support by means of a screw 54 and having six teeth 55. The gear wheel 53 is in the same plane as and

engages with the gear wheel 15 and is further adapted to cooperate with the driving pin 13 on the date member 10.

To the front frame plate 2 is rigidly secured an auxiliary shaft 56 on which is journaled a hub 57 retained by a screw 58 and carrying two gear wheels 59, 60 made integral therewith. The gear wheel 59 is in the same plane as and engages with the teeth 25 on the hub 14, and the gear wheel 60 is in the same plane as and engages with the gear wheel 28 secured to the leap year member 26.

Three pawls 61, 62, 63 are pivotally secured to a post 64 fixed to the rear frame plate 1 and engaged by springs 65, 66, 67 also secured to the rear frame plate at 68, 69. The pawl 61 engages with the teeth 16 of the gear wheel 15 and the engaging end thereof is so formed as to complete the movement of the gear wheel 15 and to adjust it to its correct positions. The pawl 62 engages with the date member 10 and serves to adjust this to its correct positions, further to prevent movement thereof except in the direction of the arrow indicated thereon. Similarly the pawl 63 engages with the week-day member 8 and serves to prevent this member from revolving except in the direction of the arrow indicated thereon.

The mechanism functions as follows.

The calendar position shown in Fig. 1 is that of the 28th of February a year which is not a leap year. In order to facilitate the understanding of the functioning of the mechanism it is, however, preferable to assume at first that the calendar position is that of the 27th of February and that the date member 10 is displaced one date step in a clockwise direction so that the pin 12, as seen in Fig. 1, is covered by the outer periphery of the month member 17. The driving member 29 is shown in its normal position. At twelve o'clock in the night it moves in an anti-clockwise direction an angle roughly corresponding to the distance between two notches 9 on the week-day member 8. The pawl 33 engages with one of the notches 9 and shifts the week-day member 8 one week-day step in the direction of the arrow indicated thereon. The pawl 34 is at first held by the guide member 50 in the inactive position but when arriving at the position shown in dotted lines at 70 it is released and after a further short movement of the driving member 29 engages with one of the teeth 11 on the date member 10 and shifts the date member one date step in the direction of the arrow, i. e., to the 28th. The pawl 35 drops into the February indentation 19 and moves along the bottom of this indentation but without engaging with the date member. The driving member 29 then returns to the normal position and the calendar now is in the position corresponding to the 28th of February, which is the position shown in Fig. 1. It is to be noted that the shifting of the date member 10 brought the pin 12 into the position shown in Fig. 1.

On the 28th of February at twelve o'clock in the night the driving member 29 again starts on its active feed movement. The week-day member 8 is shifted one step as before. The pawl 35, however, drops into the indentation 19, engages with the pin 12 and shifts the date member 10 a little more than two steps (the surplus feed), whereafter the pawl 35 moves up from the indentation 19 and releases the pin 12. At this moment, however, the feed is taken over by the pawl 34, which is now in the position indicated at 70

and engages with one of the teeth 11 of the date member 10, shown in dotted lines at 71. The pawl 34 thereafter completes the surplus feed and then shifts the date member 10 the normal step. The date member 10 is thus moved four steps 5 from the 28th direct to the 1st.

At the same time the month member 17 and the leap year member 26 are also shifted by means of the driving pin 13. When the date member 10 has moved three steps in the direction of the arrow, i. e., to the position corresponding to the 31st, the driving pin 13 is close to one of the teeth 55 on the gear wheel 53, and when the date member moves the last step from the 31st to the 1st the driving pin 13 turns the gear wheel 53 somewhat less than one sixth of a complete revolution. As the gear wheel 53 is in engagement with the gear wheel 15 this latter is turned somewhat less than one-twelfth of a complete revolution. The movement is completed 20 by the pawl 61. With the gear wheel 15 the month member 17 is also turned one-twelfth of a complete revolution in the direction of the arrow, and the gear wheel 25 by means of the gear wheels 59, 60, 28 turns the leap year member 26 25 one one-hundred-forty-fourth of a complete revolution. The calendar is now in the position corresponding to the 1st of March.

The shifting of the week-day member 8 and the date member 10 now proceeds in the normal 30 way. At the end of the March month the pin 12 is again in the position shown in Fig. 1 but is now covered by the outer periphery of the month member 17 so that no surplus feed can take place. The date member 10 is therefore shifted in the 35 normal way, i. e., one step, on the 28th and likewise on the 29th, the 30th and the 31st. Simultaneously with the shifting from the 31st to the 1st the driving pin 13 again comes into action and shifts the month member 17 and the leap year 40 member 26 as before. The April indentation 18a has now been displaced an angle of 60° in a clockwise direction, so that the side 18b thereof coincides with the side 19b of the indentation 19 in the position shown in Fig. 1. The deflecting 45 side 18c of the indentation 18 is, however, displaced an angle approximately corresponding to two date steps from the deflecting side 19c of the indentation 19. At the end of the April month the pawl 35 engages with the pin 12 but not 50 until this is in the position corresponding to the 30th, and the pawl and the pin thus shift the date member on the 30th one surplus step in addition to the normal step, i. e., from the 30th to the 1st. 55

On the 28th of February one year later the various parts are all in the positions shown in Fig. 1, except that the leap year member 26 is displaced an angle of 30° in the direction of the arrow. After the lapse of a further year 60 the cam 27a is in a position in which it engages with the projection 23 on the leap year control member 22 and holds this member in a position in which it covers the pin 12 on the 28th. There is therefore no surplus feed on the 28th of February this year and the date member is shifted only the normal step to the 29th. On the 29th, however, the pawl 35 engages with the pin 12 and causes the date member 10 to be shifted from the 29th direct to the 1st. 65 70

In Figs. 4-9 the numeral 101 denotes the rear frame plate of the calendar work and 102 the front frame plate, part of which has been broken away to show the interior mechanism. The plates are held together by four posts 103 secured 75

to the plates by means of screws 104. In holes 105 and 106 in the frame plates is revolvably mounted a shaft 107 on which the main parts of the calendar mechanism are mounted.

5 Adjacent the rear frame plate 101 is revolvably mounted on the shaft 107 a driving member 108, which in Fig. 4 is shown in its normal position and in Fig. 5 raised into its vertical position. To the driving member 108 is attached at 109 a post 110 and to this post is swingably secured by means of a screw 111 a pawl 112. The pawl 112 is provided with an elongated hole 113 through which the screw 111 passes, so that the pawl 112 has not only a swinging but also a sliding movement relatively the driving member 108. One end of the pawl 112 is formed into a point 114 adapted to cooperate with the date member described in the following. The other end of the pawl is turned up at 115 into the same plane 20 as the month member described in the following and formed into a hook 116. The driving member 108 is further provided with an extension 117 to which is fixed a stop pin 118 for limiting the swinging movement of the hook end of the pawl 112 in an inward direction. To the driving member 108 is further fixed a post 119 carrying a leaf spring 120 the free end of which rests against the pawl 112 so as to normally hold it against the stop pin 118. To the hook end of the pawl 112 is fixed a guide pin 121 adapted to cooperate with a guide member to be described in the following.

Adjacent the driving member 108 is rigidly secured to the shaft 107 a gear wheel 122 having twelve teeth 123. The gear wheel 122 is provided with a hub 124 on which is revolvably mounted the date member 125. The date member 125 is in the same plane as the point 114 of the pawl 112 and is provided with thirty-one teeth 126 adapted to cooperate with the pawl 112. To the date member 125 is fixed a driving pin 127 adapted to cooperate with a gear wheel to be described in the following. The date member 125 is further provided with an elongated opening 128, in which is located a leaf spring 129. One end of the leaf spring 129 is secured to the date member at 130 and the other end carries a surplus feed control member 131 which by the leaf spring 129 is held against the curvature of a month member to be described in the following and 45 which is broad enough in an axial direction to bear against not only the curvature of the month member but also against a leap year control member carried by the month member.

Each of the teeth 126 on the date member 125 is provided with one of the calendar indicia between 1 and 31. This is best illustrated in Fig. 7 which also shows a window 165 provided in a suitable position in the structure for reading the indicia, preferably in the front plate 102. 60 To the shaft 107 is further rigidly secured the month member 132 which is in the same plane as and is adapted to cooperate with the hook end 116 of the pawl 112. The month member 132 is provided with four short cams 133, corresponding to the four thirty day months in the year, and further with a cam 134 which has about twice the peripheral length of the aforesaid cams and which corresponds to the February month. An arm 135 is swingably secured 65 to the month member by a screw 136 and the free end of this arm is formed into a leap year control member 137 adapted to cooperate with the surplus feed control member 131 and further with a leap year member to be described in the following. The leap year control member is pro-

vided with a projection 138 adapted to bear against the said leap year member. The movement of the arm 135 is limited in an outward direction by a stop pin 139 fixed to the month member 132.

5 The month member 132 is provided with a hub 140 and on this hub is revolvably mounted a leap year member 141 made integral with a gear wheel 142, part of which has been broken away in Fig. 1. The leap year member 141 is provided with three indentations 143 adapted to cooperate with the projection 138 on the leap year control member 137.

10 Adjacent the gear wheel 142 is rigidly secured to the shaft 107 a gear wheel 144.

A gear wheel 145 is revolvably secured to the rear frame plate 101 by means of a screw 146 and engages with the twelve-toothed gear wheel 122. The six-toothed gear wheel 145 is adapted to be actuated by the driving pin 127 on the date member 125.

15 Two gear wheels 147, 148 made integral are revolvably mounted on the front frame plate 102 by means of a screw 149. The gear wheel 147 engages with the gear wheel 144 secured to the shaft 107, and the gear wheel 148 engages with the gear wheel 142 made integral with the leap year member 141. It will be seen that when the driving pin 127 actuates the six-toothed gear wheel 145 in the direction indicated by the arrow 20 the month member 132 and the leap year member 141 are also turned in the directions indicated by the arrows. This action is the same as explained with reference to Figs. 1-3.

A guide member 150 is attached to or made integral with the front frame plate 102 and adapted 35 to cooperate with the guide pin 121 on the pawl 112.

Two pawls 151, 152 are pivotally secured by means of a screw 153 to a post 154 fixed to the rear frame plate 101 and engaged by springs 40 155, 156. The spring 155 is secured to the rear frame plate at 157. The spring 156 is secured to a post 158 fixed to the rear frame plate. The pawl 151 engages with the teeth 123 of the twelve toothed gear wheel 122, and the engaging 45 end 159 thereof is so formed as to complete the movement of the gear wheel 122 and to adjust it to its correct position. The pawl 152 engages with the teeth 126 of the date member 125 and serves to hold this in its correct position, further 50 to prevent movement thereof except in the direction of the arrow.

The mechanism functions as follows.

The calendar position shown in Fig. 4 is that corresponding to the 28th of February a year 55 which is not a leap year. In order to facilitate the understanding of the functioning of the mechanism it is, however, preferable to assume at first that the calendar is in the position which corresponds to the 27th of February and that 60 the date member 125 is displaced one step in a clockwise direction so that the surplus step control member 131 attached to the date member has not yet mounted the leap year control member 137. In this position the indicium 27 65 appears in the window 165.

The driving member 108 is shown in Fig. 4 in its normal position. At twelve o'clock in the night it moves inactively to the position indicated in dotted lines at A in Fig. 4 and in full lines in Fig. 7. During this movement the guide pin 121 at first glides along the upper face of the guide member 150 but the pivotal and sliding connection of the pawl 112 enables the point 70 75

114 to slide over the teeth 126 of the date member 125. The guide pin 121 is then released from the guide member 150 so that the pawl 112 comes to rest against the stop pin 118 and the point 114 is turned up from the teeth 126. When the driving member returns from the position shown at A to its normal position, the pawl 112 at first remains at rest against the stop pin 118, but when the driving member 108 has moved an angle corresponding to somewhat more than two steps of the date member 125 the guide pin 121 runs up on the guide member 150 and the point 114 is forced down into engagement with one of the teeth 126, thus shifting the date member 125 one date step, i. e., from the 27th to the 28th. At the same time the surplus control member 131 moves one step in the same direction as the date member 125 and mounts the leap year control member 137, as shown in Fig. 4. The position of the various parts is now exactly that shown in Fig. 4.

At twelve o'clock on the 28th of February the driving member again moves to the position indicated at A, but this time the hook 116 is forced up on the surplus feed control member 131 so that the point 114 is forced into engagement with the tooth 126a as shown in Fig. 7. When the driving member 108 returns to its normal position the surplus feed control member 131 moves along the periphery of the leap year control member 137 and the ordinary February cam 134, thus maintaining the pawl 112 in engagement with the tooth 126a. The guide pin 121 then runs up on the guide member 150 and takes over the feed when the surplus feed control member drops down on the other side of the February cam 134. In this manner the date member 125 is shifted in one operation from the 28th direct to the 1st that is to say the indicium 1 now appears in the window 165.

When the date member 125 is shifted from the 31st to the 1st the driving pin 127 engages with the six toothed gear wheel 145 and shifts the month member 132 and the leap year member 141 in exactly the same way as described with reference to Figs. 1-3. The calendar is now in the position corresponding to the 1st of March, and the shifting of the date member 125 proceeds in the normal way. On the 28th of March the surplus feed control member 131 is again in the position shown in Fig. 1 but now rests against a part of the month curvature where there is no cam and therefore does not actuate the pawl 112. The date member 125 is therefore shifted in the normal way, i. e., only one step for each effective movement of the driving member 108. Simultaneously with the shifting from the 31st to the 1st the driving pin 127 again comes into action and shifts the month member 132 and the leap year member 141 as before. The April cam 133a now occupies the position of the February cam 134 as shown in Fig. 1, and at the end of the month the pawl 112 engages with the date member 125 on the 30th so as to shift this member from the 30th direct to the 1st.

On the 28th of February two years later the indentation 143a of the leap year member 141 is in a position in which it cooperates with the projection 138 on the leap year control member 137, so that the outer periphery of the leap year control member 137 is below the level of the cam 134. There is therefore no surplus feed on the 28th of February this year. On the 29th of February, however, the surplus feed control member 131 has mounted the ordinary February cam

134 and causes the date member 125 to be shifted from the 29th direct to the 1st.

The leap year member may be provided with indications or the like indicating whether the current year is a leap year or not and also what the position of the current year is in the leap year period, as shown at 160 in Fig. 4. The line, when in the upper position, indicates that the current year is a leap year, and the dots, when in the upper position, indicate that the current year is a year before or after leap year.

It is to be noted that in the embodiments shown the cams and the indentations are displaced relatively to each other angles of 60, 60, 90, 60 and 90 degrees respectively.

Characteristic for my invention is the special shape of the surplus feed control curvature, the members 35 and 112 which move in contact with the surplus feed control curvature during the surplus feed period and in one case control and effect the surplus feed and in the other case control the engagement of the feed member for effecting the surplus feed, that the lengths of the cams 133, 134 or the indentations 18, 19 are utilized for maintaining the engagement of the surplus feed member with the date member during the surplus feed, the transfer of the surplus feed to the normal feed at a point where the surplus feed is not completed, that in the embodiment shown in Figs. 4-9 the same feed member is utilized for effecting the normal as well as the surplus feed, the movable leap year control member for controlling the surplus feed at the end of February, the leap year member for controlling the movements of the leap year control member, the providing of the leap year member with indications indicating the position of the current year in the leap year period and the simplicity of the whole construction.

What I claim as new and desire to secure by Letters Patent of the United States of America is:

1. A perpetual date calendar comprising a revoluble date member adapted to be moved step by step, a revoluble month member adapted to be moved step by step and provided with a surplus feed control curvature having deflections for controlling the surplus feed of the date member angularly displaced, but having the same radial displacement relatively to each other, in month and date steps so as to control the surplus feed of the date member merely by their angular displacements, means operative to advance the month member a complete month step for each shifting of the date member from the position corresponding to the thirty-first of one month to the position corresponding to the first of the following month, a feed mechanism for the date member having a reciprocating movement corresponding to at least the greatest number of date steps required for shifting the date member from the last day of one month to the first day of the following month and operative to effect the normal one-step feed of the date member, and means having an angular motion about the axis of the month member and adapted for each operation of the feed mechanism at the end of a month to move along and in contact with that part of the surplus feed control curvature of the month member which is in the operative position and together with the feed mechanism control and effect the surplus feed of the date member.

2. A perpetual date calendar comprising a revoluble date member adapted to be moved step by step, a revoluble month member adapted to

- be moved step by step and provided with a surplus feed control curvature having peripheral guide faces comprising cams and indentations integral with the month member, the angular sides 5 of which are adapted to determine the time for operation of the surplus feed and the peripheral lengths of which are adapted to determine the length of the surplus feed, means operative to advance the month member a complete month 10 step for each shifting of the date member from the position corresponding to the thirty-first of one month to the position corresponding to the first of the following month, a feed mechanism for the date member having a reciprocating movement corresponding to at least the greatest number of date steps required for shifting the date member from the last day of one month to the first day of the following month and operative to effect the normal one-step feed of the date member, and means having an angular motion about the axis of the month member and adapted for each operation of the feed mechanism at the end of a month to move along and in contact with that part of the surplus feed 15 control curvature of the month member which is in the operative position and together with the feed mechanism control and effect the surplus feed of the date member.

3. A perpetual date calendar comprising a revoluble date member adapted to be moved step by step, a revoluble month member adapted to be moved step by step and provided with a surplus feed control curvature having deflections for controlling the surplus feed of the date member angularly displaced but having the same radial displacement relatively to each other in month and date steps so as to control the surplus feed of the date member merely by their angular displacements, means operative to advance the 20 month member a complete month step for each shifting of the date member from the position corresponding to the thirty-first of one month to the position corresponding to the first of the following month, a feed mechanism for the date member having a reciprocating movement corresponding to at least the greatest number of date steps required for shifting the date member from the last day of one month to the first day of the following month and operative to effect the normal one-step feed of the date member and part of the surplus feed, and means having an angular motion about the axis of the month member and adapted for each operation of the feed mechanism at the end of a month to move along and in contact with that part of the surplus feed control curvature of the month member which is in the operative position and together with the feed mechanism control and effect the surplus feed of the date member.

4. A perpetual date calendar comprising a revoluble date member adapted to be moved step by step, a revoluble month member adapted to be moved step by step and provided with a surplus feed control curvature having deflections for controlling the surplus feed of the date member angularly displaced but having the same radial displacement relatively to each other in month and date steps so as to control the surplus feed of the date member merely by their angular displacements, means operative to advance the month member a complete month step for each shifting of the date member from the position corresponding to the thirty-first of one month to the position corresponding to the first of the following month, a feed mechanism for the date member having a reciprocating movement corresponding to at least the greatest number of date steps required for shifting the date member from the last day of one month to the first day of the following month and operative to cause the feed member to move into the operative position during the later part of the active feed of the feed mechanism and at a point behind the point at which a feed engagement is required for effecting the normal feed of the date member, and means having an angular motion about the axis of the month member and adapted for each operation of the feed mechanism at the end of a month to move along and in contact with that part of the surplus feed control curvature of the month member which is in the operative position and together with the feed mechanism control and effect the surplus feed of the date member.

5. A perpetual date calendar comprising a revoluble date member adapted to be moved step by step, a revoluble month member adapted to be moved step by step and provided with a surplus feed control curvature having deflections for controlling the surplus feed of the date member angularly displaced but having the same radial displacement relatively to each other in month and date steps so as to control the surplus feed of the date member merely by their angular displacements, a leap year control member cooperating with the surplus feed control curvature of the month member, a revoluble leap year member cooperating with the leap year control member, means operative to advance the month member a complete month step for each shifting of the date member from the position corresponding to the thirty-first of one month to the position corresponding to the first of the following month, means for advancing the leap year member responsive to the movement of the month member, a feed mechanism for the date member having a reciprocating movement corresponding to at least the greatest number of date steps required for shifting the date member from the last day of one month to the first day of the following month and operative to effect the normal one-step feed of the date member, and means having an angular motion about the axis of the month member and adapted for each operation of the feed mechanism at the end of a month to move along and in contact with that part of the surplus feed control curvature of the month member which is in the operative position and together with the feed mechanism control and effect the surplus feed of the date member.

6. A perpetual date calendar comprising a revoluble date member adapted to be moved step by step, a revoluble month member adapted to be moved step by step and provided with a surplus feed control curvature having deflections for controlling the surplus feed of the date member angularly displaced but having the same radial displacement relatively to each other in month and date steps so as to control the surplus feed of the date member merely by their angular displacements, a leap year control member cooperating with the surplus feed control curvature of the month member and movable from an operative to an inoperative position, a revoluble leap year member cooperating with the leap year control member and operative to move the date member having a reciprocating movement corresponding to at least the greatest number of date steps required for shifting the date member from the last day of one month to the first day of the following month and including a feed member for the normal one-step feed of the date member movable from an inoperative to an operative position and vice versa, means cooperating with the feed member and operative to cause the feed member to move into the operative position during the later part of the active feed of the feed mechanism and at a point behind the point at which a feed engagement is required for effecting the normal feed of the date member, and means having an angular motion about the axis of the month member and adapted for each operation of the feed mechanism at the end of a month to move along and in contact with that part of the surplus feed control curvature of the month member which is in the operative position and together with the feed mechanism control and effect the surplus feed of the date member.

year member from the operative to the inoperative position and vice versa, means operative to advance the month member a complete month step for each shifting of the date member from the position corresponding to the thirty-first of one month to the position corresponding to the first of the following month, means operative to advance the leap year member for each advancement of the month member, a feed mechanism for the date member having a reciprocating movement corresponding to at least the greatest number of date steps required for shifting the date member from the last day of one month to the first day of the following month and operative to effect the normal one-step feed of the date member, and means having an angular motion about the axis of the month member and adapted for each operation of the feed mechanism at the end of a month to move along and in contact with that part of the surplus feed control curvature of the month member which is in the operative position and together with the feed mechanism control and effect the surplus feed of the date member.

5 7. A perpetual date calendar comprising a revoluble date member adapted to be moved step by step, a revoluble month member adapted to be moved step by step and provided with a surplus feed control curvature having peripherical 10 guide faces comprising cams and indentations integral with the month member the angular sides of which are adapted to determine the time for operation of the surplus feed and the peripherical lengths of which are adapted to determine the length of the surplus feed, a leap year control member cooperating with the surplus feed control curvature of the month member and movable from an operative to an inoperative position, a revoluble leap year member cooperating 15 with the leap year control member and operative to move the leap year member from the operative to the inoperative position and vice versa, means operative to advance the month member a complete month step for each shifting of the date member from the position corresponding to the thirty-first of one month to the position corresponding to the first of the following month, means operative to advance the leap year member for each advancement of the month member, a feed mechanism for the date member having a reciprocating movement corresponding to at least the greatest number of date steps required 20 for shifting the date member from the last day of one month to the first day of the following month and operative to effect the normal feed of the date member, and a surplus feed member adapted to move with the feed mechanism in contact with the surplus feed control curvature of the month member and operative to effect the surplus feed of the date member responsive to the surplus feed control curvature of the month member.

25 8. A perpetual date calendar comprising a revoluble date member having at least thirty-one date steps and adapted to be shifted step by step, a revoluble month member having twelve month steps, adapted to be shifted step by step and provided with a surplus feed control curvature having indentations integral with the month member and angularly displaced, relatively to each other, so as to control the point of engagement for effecting the surplus feed of the date member. 30 9. A perpetual date calendar comprising a revoluble date member having at least thirty-one date steps and adapted to be shifted step by step, a revoluble month member having twelve month steps, adapted to be shifted step by step and provided with a surplus feed control curvature having indentations integral with the month member and angularly displaced, relatively to each other, so as to control the point of engagement for effecting the surplus feed of the date member. 35 10. A perpetual date calendar comprising a revoluble date member having at least thirty-one date steps and adapted to be shifted step by step, a revoluble month member having twelve month steps, adapted to be shifted step by step and provided with a surplus feed control curvature having indentations integral with the month member and angularly displaced, relatively to each other, so as to control the point of engagement for effecting the surplus feed of the date member. 40 11. A perpetual date calendar comprising a revoluble date member having at least thirty-one date steps and adapted to be shifted step by step, a revoluble month member having twelve month steps, adapted to be shifted step by step and provided with a surplus feed control curvature having indentations integral with the month member and angularly displaced, relatively to each other, so as to control the point of engagement for effecting the surplus feed of the date member. 45 12. A perpetual date calendar comprising a revoluble date member having at least thirty-one date steps and adapted to be shifted step by step, a revoluble month member having twelve month steps, adapted to be shifted step by step and provided with a surplus feed control curvature having indentations integral with the month member and angularly displaced, relatively to each other, so as to control the point of engagement for effecting the surplus feed of the date member. 50 13. A perpetual date calendar comprising a revoluble date member having at least thirty-one date steps and adapted to be shifted step by step, a revoluble month member having twelve month steps, adapted to be shifted step by step and provided with a surplus feed control curvature having indentations integral with the month member and angularly displaced, relatively to each other, so as to control the point of engagement for effecting the surplus feed of the date member. 55

14. A perpetual date calendar comprising a revoluble date member having at least thirty-one date steps and adapted to be shifted step by step, a revoluble month member having twelve month steps, adapted to be shifted step by step and provided with a surplus feed control curvature having indentations integral with the month member and angularly displaced, relatively to each other, so as to control the point of engagement for effecting the surplus feed of the date member, means for shifting the month member responsive to the movement of the date member, a feed mechanism for the date member having a reciprocating feed movement corresponding to at least the greatest number of date steps required for shifting the date member from the last day of one month to the first day of the following month and including a feed member operative to effect the normal feed of the date member, and a surplus feed member for effecting the surplus feed of the date member adapted to move with the feed mechanism in contact with the surplus feed control curvature of the month member and operative to effect the surplus feed of the date member responsive to the surplus feed control curvature of the month member.

15. A perpetual date calendar comprising a revoluble date member having at least thirty-one date steps and adapted to be shifted step by step, a revoluble month member having twelve month steps, adapted to be shifted step by step and provided with a surplus feed control curvature having indentations integral with the month member and angularly displaced, relatively to each other, so as to control the point of engagement for effecting the surplus feed of the date member, means for shifting the month member responsive to the movement of the date member, a leap year control member cooperating with the surplus feed control curvature of the month member and movable from an operative to an inoperative position, a revoluble leap year member cooperating with the leap year control member and operative to move the leap year control member from the inoperative to the operative position, 70 and operative to move the leap year control member from the inoperative to the operative position, 75

- means for advancing the leap year member for each advancement of the month member, and a feed mechanism for the date member having an effective feed movement corresponding to at least 5 four date steps of the date member and including a feed member operative to effect the normal feed of the date member, and a surplus feed member for effecting the surplus feed of the date member adapted to move with the feed mechanism in contact with the surplus feed control curvature of the month member 10 for effecting the surplus feed of the date member responsive to the surplus feed control curvature of the month member.
12. A perpetual date calendar comprising a date member in the form of a revoluble disc having thirty-one teeth and adapted to be shifted step by step, a month member in the form of a revoluble disc coaxial with the date member, having twelve teeth, adapted to be shifted step by step and provided with indentations along its periphery displaced relatively to each other approximately 60, 60, 90, 60 and 90 degrees and having peripherical lengths effective for controlling the surplus feed of the date member, a gear wheel having six teeth meshing with the teeth of the month member, means for causing the date member for each shifting thereof from the last day of one month to the first day of the following month to shift the six-toothed gear wheel one tooth, a feed mechanism for the date member having a reciprocating movement about the common axis of the date and month members corresponding to at least the greatest number of date steps required for shifting the date member from the last day of one month to the first day of the following month and including a normal feed member operative to engage with the teeth of the date member and to shift the date member one step for each active feed movement of the feed mechanism, and a surplus feed member adapted to move with the feed mechanism and to engage with the date member at one point thereof and to move in contact with the indented periphery of the month member and thereby effect the surplus feed of the date member responsive to the indentations of the month member.
13. A perpetual date calendar comprising a date member in the form of a revoluble disc having thirty-one teeth and adapted to be shifted step by step, a month member in the form of a revoluble disc coaxial with the date member, having twelve teeth, adapted to be shifted step by step and provided with indentations along its periphery displaced relatively to each other approximately 60, 60, 90, 60 and 90 degrees and having peripherical lengths effective for controlling the surplus feed of the date member, a gear wheel having six teeth meshing with the teeth of the month member, means for causing the date member for each shifting thereof from the last day of one month to the first day of the following month to shift the six-toothed gear wheel one tooth, a leap year control member movably secured to the month member so as to cooperate with one of the indentations in the month member and movable from an inoperative to an operative position, a leap year member in the form of a revoluble disc coaxial with the date and month members and having a leap year control curvature cooperating with the leap year control member, a gear connecting the leap year member with the month member and operative to advance the leap year member for each advance- 50
- ment of the month member, a feed mechanism for the date member having a reciprocating movement about the common axis of the date and month members corresponding to at least the greatest number of date steps required for shifting the date member from the last day of one month to the first day of the following month and including a normal feed member operative to engage with the teeth of the date member and to shift the date member one step for each active feed movement of the feed mechanism, and a surplus feed member movable with the feed mechanism and operative to engage with the date member at one point thereof and to move in contact with the indented periphery of the month member and thereby effect the surplus feed of the date member responsive to the indentations of the month member.
14. A perpetual date calendar comprising a revoluble date member adapted to be moved step by step, a revoluble month member adapted to be moved step by step and provided with a surplus feed control curvature having deflections the angular displacements of which, relatively to each other, are effective for controlling the surplus feed of the date member, means operative to advance the month member one month step for each shifting of the date member from the last day of one month to the first day of the following month, a feed mechanism for the date member having a reciprocating movement corresponding to at least the greatest number of date steps required for shifting the date member from the last day of one month to the first day of the following month and including a feed member operative to effect the normal as well as the surplus feed of the date member, and a surplus feed control member adapted to move with the date member in contact with the surplus feed control curvature of the month member and to cooperate with the feed member of the feed mechanism for controlling the surplus feed of the date member.
15. A perpetual date calendar comprising a revoluble date member having at least thirty one date steps and adapted to be shifted step by step, a revoluble month member having twelve month steps, adapted to be shifted step by step and provided with a surplus feed control curvature having cams integral with the month member and angularly displaced, relatively to each other, so as to control the point of engagement for effecting the surplus feed of the date member, means for shifting the month member responsive to the movement of the date member, a feed mechanism for the date member having a reciprocating movement corresponding to at least the greatest number of date steps required for shifting the date member from the last day of one month to the first day of the following month and including a feed member operative to effect the normal as well as the surplus feed of the date member, and a surplus feed control member adapted to move with the date member in contact with the surplus feed control curvature of the month member and to cooperate with the feed member of the feed mechanism for controlling the surplus feed of the date member responsive to the surplus feed control curvature of the month member.
16. A perpetual date calendar comprising a revoluble date member having at least thirty one date steps and adapted to be shifted step by step, a revoluble month member having twelve month steps, adapted to be shifted step by step and

provided with a surplus feed control curvature having cams integral with the month member and angularly displaced, relatively to each other, so as to control the point of engagement for effecting the surplus feed of the date member, means for shifting the month member responsive to the movement of the date member, a leap year control member cooperating with the surplus feed control curvature of the month member and movable from an inoperative to an operative position, a revolute leap year member cooperating with the leap year control member and operative to move the leap year control member from the inoperative to the operative position, means for advancing the leap year member for each advancement of the month member, a feed mechanism for the date member having a reciprocating movement corresponding to at least four date steps of the date member and provided with a feed member operative to effect the normal as well as the surplus feed of the date member, and a surplus feed control member adapted to move with the date member in contact with the surplus feed control curvature of the month member and to cooperate with the feed member of the feed mechanism for controlling the surplus feed of the date member responsive to the surplus feed control curvature of the month member.

17. A perpetual date calendar comprising a date member in the form of a revolute disc having thirty one teeth and adapted to be shifted step by step, a month member in the form of a revolute disc coaxial with the date member, having twelve teeth, adapted to be shifted step by step and provided with cams along its periphery displaced relatively to each other approximately 60, 60, 90, 60 and 90 degrees and having peripheral lengths effective for controlling the surplus feed of the date member, a gear wheel having six teeth meshing with the teeth of the month member, means for causing the date member for each shifting thereof from the last day of one month to the first day of the following month to shift the six-toothed gear wheel one tooth, a leap year control member movably secured to the month member so as to cooperate with one of the cams of the month member and movable from an inoperative to an operative position, a leap year member in the form of a revolute disc coaxial with the date and month members and having a leap year control curvature cooperating with the leap year control member, a gear connecting the leap year member with the month member and operative to advance the leap year member for each advancement of the month member, a feed mechanism for the date member having an effective feed movement corresponding to at least four date steps of the date member and provided with a feed member operative to effect the normal as well as the surplus feed of the date member, and a surplus feed control member adapted to move with the date member in contact with the projected periphery of the month member and to cooperate with the feed member of the feed mechanism for controlling the surplus feed of the date member responsive to the surplus feed control curvature of the month member.

the date member, and a surplus feed control member adapted to move with the date member in contact with the projected periphery of the month member and to cooperate with the feed member of the feed mechanism for controlling the surplus feed of the date member responsive to the surplus feed control curvature of the month member.

18. A perpetual date calendar comprising a date member in the form of a revolute disc having thirty one teeth and adapted to be shifted step by step, a month member in the form of a revolute disc coaxial with the date member, having twelve teeth, adapted to be shifted step by step and provided with cams along its periphery displaced relatively to each other approximately 60, 60, 90, 60 and 90 degrees and having peripheral lengths effective for controlling the surplus feed of the date member, a gear wheel having six teeth meshing with the teeth of the month member, means for causing the date member for each shifting thereof from the last day of one month to the first day of the following month to shift the six-toothed gear wheel one tooth, a leap year control member movably secured to the month member so as to cooperate with one of the cams of the month member and movable from an inoperative to an operative position, a leap year member in the form of a revolute disc coaxial with the date and month members and having a leap year control curvature cooperating with the leap year control member, a gear connecting the leap year member with the month member and operative to advance the leap year member for each advancement of the month member, a feed mechanism for the date member having an effective feed movement corresponding to at least four date steps of the date member and provided with a feed member operative to effect the normal as well as the surplus feed of the date member, and a surplus feed control member adapted to move with the date member in contact with the projected periphery of the month member and to cooperate with the feed member of the feed mechanism for controlling the surplus feed of the date member responsive to the surplus feed control curvature of the month member.

JOSUA GABRIEL PAULIN.
